DESIGN FOR A HOLDER FOR PLATE, CUP, AND IMPLEMENT

Joseph K. Laier, Kansas City, Mo.

Application February 24, 1948, Serial No. 144,673

Term of patent 14 years

(Cl. D44—10)

To all whom it may concern:

Be it known that I, Joseph K. Laier, a citizen of the United States, residing at Kansas City, in the county of Jackson and State of Missouri, have invented a new, original, and ornamental Design for a Holder for Plate, Cup, and Implement, of which the following is a specification, reference being had to the accompanying drawing, forming a part thereof.

Figure 1 is a plan view of the holder for plate, cup, and implement, showing my new design.

Fig. 2 is a side elevational view thereof.

Fig. 3 is an elevational view of one end thereof; and

Fig. 4 is an elevational view of the opposite end thereof.

I claim:

The ornamental design for a holder for plate, cup, and implement, as shown.

JOSEPH K. LAIER.
